(57) CLAIM

The ornamental design for a pet cleaning cart, as shown and described.

DESCRIPTION

This application corresponds to subject matter to that of Disclosure Document Deposit No. 482,301 dated Nov. 13, 2000.

FIG. 1 is a top perspective view of a pet cleaning cart showing my new design;

FIG. 2 is a front elevation view thereof;

FIG. 3 is a front elevation view thereof;

FIG. 4 is a right side elevation view thereof, the left side view being a mirror image of that shown;

FIG. 5 is a top plan view thereof; and,

FIG. 6 is a bottom plan view thereof.

The portions of legs in FIGS. 2, 3 and 4 are shown broken away for convenience of illustration, and the broken line illustration of bag in FIG. 4 is for illustrative purposes only and forms no part of the claimed design.
